UNITED STATES PATENT OFFICE.

FREDERICK WILLIAM HOLLAND, OF BROOKLYN, NEW YORK, ASSIGNOR TO HERMAN SCHEUER, JACOB H. SCHEUER, AND ALWIN J. SCHEUER, COPARTNERS DOING BUSINESS UNDER THE FIRM-NAME OF HERMAN SCHEUER & SONS, OF BROOKLYN, NEW YORK.

ADJUSTABLE KIT.

1,265,331.

Specification of Letters Patent.

Patented May 7, 1918.

Application filed February 11, 1918. Serial No. 216,542.

To all whom it may concern:

Be it known that I, FREDERICK W. HOLLAND, a citizen of the United States, residing at the borough of Brooklyn, in the city of New York, county of Kings, and State of New York, have invented certain new and useful Improvements in Adjustable Kits, of which the following is a specification.

10 This invention relates to certain new and useful improvements in adjustable kits and especially to that type embodying a retaining strap which is threaded selectively through a plurality of slots or eyes formed 15 in a strap-engaging means secured to the case to provide a series of article-receiving loops in which various articles are disposed and subsequent to which said strap is pulled to contract the loops and thereby tighten 20 the grip of the strap about the confined articles.

The principal object of the invention resides in a simple lock or securing means for the free end of the retaining strap by which 25 the same is firmly held against slipping and the loops against consequential enlargement which would necessarily loosen the articles contained in the kit.

The invention seeks to provide a simple 30 lock in the form of a pair of transversely arranged flaps which is secured to the casing so that said flaps may be folded across the backwardly folded free end of the retaining strap and secured by a detachable 35 fastener for securely locking the strap against slipping.

In the drawing—

Figure 1 is a fragmentary plan view of a kit embodying the present invention and 40 showing the same operative;

Fig. 2 is a similar view in which the locking or securing strap is inoperative; and

Fig. 3 is a transverse section on line 3—3 45 of Fig. 1 further illustrating the invention.

Referring more in detail to the drawings, the body or casing 1 of the kit is sheet-like in form, being of canvas, leather or some other desirable and flexible material that is 50 capable of being readily folded and rolled in packet formation. Secured to this flexible and sheet-like casing, in the direction

of roll, is a strap-engaging means or strip 2 which is stitched along its edges, as at 3, to leave the intermediate or longitudinal 55 central portion free of the casing to facilitate the introduction and threading of the retaining strap 4 through the slots or eyes 5 and beneath said strip. The slots or eyes 5 are formed transversely in said strip at 60 practically regular intervals throughout its length. The retaining or adjustable strap 4 is anchored beneath the inner end of the strip 2 and is adapted for having its free end selectively threaded down and up 65 through the slots 5 to form article-receiving loops 6 of variable sizes and distances apart.

A locking or securing strap 7 is arranged transversely across the outer end of the strip 2, being stitched at spaced points intermediate its ends to provide a central loop or passage 8 and end flaps 9. When the retaining strap 4 has been formed into the desired size and number of loops 6, the free end is threaded through the passage 8 and 75 then given a return bend or fold to overlie the locking strap 7 subsequent to which the end flaps 9 are brought over the backwardly folded free end of strap 4 and detachably connected by a snap fastener 10, the head 80 part being fixed to one flap and the socket part attached to the companion flap. The free end is thus firmly and securely fastened to hold the strap 4 against slipping through the eyes 5 and thereby loosening the strap 85 about the articles through the consequential enlargement of the loops 6.

The flaps 9 are readily connected and unlocked by the simple arrangement provided. The strap 4 is firmly held from loosening 90 its grip upon the articles, and the free end is secured firmly both for locking the strap and for holding the free end out of the way. The lock is simple and neat, requiring practically no additional kit space, and it may 95 be economically applied to the kit during manufacture with no appreciable added expense.

What is claimed is:—

1. In an adjustable kit or the like, a casing, a strap secured at one end to the casing and having its opposite end free, a fastening strap for the free end of the first named strap, means to secure the fastening strap 100

- to the casing at spaced points to form a loop for the reception of the free end portion of the first named strap, said fastening strap having each of its ends free and of 5 a length to mutually overlap, and interengaging means borne by the respective ends of the fastening strap, the free end of the first named strap being adapted to be superimposed on and over the loop-forming part 10 of the fastening strap and to be held thereon by the overlapped and fastened ends of the latter, the securing means for the fastening strap providing pivotal points for the respective ends of the fastening strap to allow 15 such ends to be moved about such points to lock and remove the free end of the first named strap without threading of the latter.
2. In combination with a casing or the like, and a strap secured at one end thereto, 20 and having its opposite end free, means for holding said free end of the strap including a fastening strap, means to secure said fastening strap to the casing at points spaced a distance apart equaling approximately the width of the first named strap, said fastening strap having its ends free and of such length so as to overlap each other, and interengaging fastening means borne by the respective free ends of the fastening strap whereby to secure such ends together, said 25 free ends of the fastening strap being movable about the respective securing means thereof so as to enable the free end of the first named strap to be placed upon and removed from over the fastening strap by 30 moving said free ends of the fastening straps about said securing means as pivots, whereby to allow the free end of the first named strap to be placed upon and removed from the fastening strap without threading. 35 40

FREDERICK WILLIAM HOLLAND.
